GLARE FILTER FOR MOTOR VEHICLES

Edward F. Piwcynski and Roman Galinski,
New Britain, Conn.

Application May 22, 1948, Serial No. 146,518

Term of patent 7 years

(Cl. D14—6)

To all whom it may concern:

Be it known that we, Edward F. Piwcynski and Roman Galinski, citizens of the United States of America, both residing in New Britain, Hartford County, Connecticut, have invented a new, original, and ornamental Design for Glare Filters for Motor Vehicles, of which the following is a specification, reference being had to the accompanying drawing, forming a part thereof.

In the drawing:

Fig. 1 is a front elevational view of a glare filter for motor vehicles, showing our new design, and

Fig. 2 is a sectional view taken on line 2—2 of Fig. 1.

The characteristic features of our design reside in the portions shown by means of full lines in the drawing.

We claim:

The ornamental design for a glare filter for motor vehicles, substantially as shown and described.

EDWARD F. PIWCZYNISKI.
ROMAN GALINSKI.
